CLAIM

The ornamental design for electrode plate, as shown and described.

DESCRIPTION

FIG. 1 is a reference perspective view of an electrode plate illustrating our new design,

FIG. 2 is a top plan view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

1 Claim, 7 Drawing Sheets
